WILLIAM A. COBB, OF ORANGE, MASSACHUSETTS.

Letters Patent No. 88,012, dated March 23, 1869.

IMPROVEMENT IN PROJECTILES.

The Schedule referred to in these Letters Patent and making part of the same.

To all whom it may concern:

Be it known that I, WILLIAM A. COBB, of Orange, in the county of Franklin, and State of Massachusetts, have invented a new and useful Improvement in Projectiles; and I do hereby declare that the following is a full, clear, and exact description thereof, which will enable others skilled in the art to make and use the same, reference being had to the accompanying drawing, forming part of this specification, in which—

Figure 1 is a longitudinal central section of my invention.

Figure 2 is a front-end view of the same.

Similar letters of reference indicate like parts.

This invention relates to a new and improved projectile; and

It consists in the combination of an internal shell, having a screw-rod extending through it, and secured therein by a nut, a can of coarse powder, and a can of fine powder, with an external rifled shell, all being arranged in such a manner that the missile, or projectile, when discharged from the gun, or piece of ordnance, and coming in contact with any body affording sufficient resistance, will have the charge within it exploded, and the internal shot projected from the external one, thereby greatly increasing the efficiency of ordnance.

In the accompanying sheet of drawings—

A represents the external shell or shot, which is of cylindrical form, and tapering at its front end:

This outer shell has a longitudinal opening, or hole *a* in it, to receive a shot, B, the outer end of which is reduced nearly to a point, to form, when B is fitted within A, a conical front end for the projectile, as shown clearly in fig. 1.

At the rear of the opening, or hole in A which receives B, there is a smaller opening, *b*, which receives a can, C.

The latter contains a charge, D, of coarse powder, said can being provided with a flange, *a'*, at its outer end, to bear against a shoulder, *e*, formed by the difference between the diameters of the openings, or holes *a* and *b*. (See fig. 1.)

E is a washer, which may be constructed of lead or

other suitable material, and interposed between the can C and the inner end of the internal shot B; and

F is a tube, which is fitted within C, and is provided with a flange, *d*, at its outer end, to screw into C.

The inner end of the tube F is stopped with a cut wad, *e*, and said tube is filled with a charge, *f*, of fine powder.

In the outer end, or cover of the tube F, there is an opening, in which a percussion-cap, or small pistol-cartridge, H, is fitted; and

I is a rod, which passes longitudinally and centrally through the internal shot B, said rod being prevented from dropping out from B by a nut, *g*, on its inner end. The outer end of the rod I projects somewhat beyond the internal shot B.

Both shots, A and B, are provided with a packing, *h*, at their inner ends.

The projectile, when the several parts are all adjusted and fitted together as shown in fig. 1, is ready for use.

I would remark that the nut *g* is so adjusted on the rod I, that a requisite amount of play is allowed to admit of the inner end of the rod being drawn from the cap H when the projectile is stored away, and the rod I may be retained in this outward position, to prevent casual or premature explosion, by any suitable means.

I would further remark that both shots may be rifled, if desired.

I am aware that compound projectiles have heretofore been made, composed of major and minor projectiles, having an interposed charge and fulminate priming, but this I do not claim.

Having thus described my invention,

I claim as new, and desire to secure by Letters Patent—

The rifled internal shot B, having a central longitudinal passage, the screw-rod I, nut *g*, can C of coarse powder, can F of fine powder, and the cartridge, or cap H, in combination with the rifled external shell, or shot A, as herein described for the purpose specified.
